DIMITRI N. HAPKINS, OF LOS ANGELES, CALIFORNIA, ASSIGNOR OF TWENTY PER CENT TO MARGARET A. KERR, OF LOS ANGELES, CALIFORNIA, AND TEN PER CENT TO CLARENCE L. KINCAID, OF LOS ANGELES, CALIFORNIA

ROTARY PUMP

Application filed January 10, 1930. Serial No. 419,842.

This invention relates to rotary pumps, compressors, superchargers and the like, and has for its general purpose to provide a simply constructed mechanism of this character having a large pumping capacity, and capable of compressing fluids in single stage operation, to high pressures.

The present form of pump may be characterized in general as comprising a rotor mounted eccentrically within a cylinder and carrying a plurality of radially movable impellers which act to compress the fluid in the peripheral clearance space between the casing and rotor. The rotor is positioned in the casing so as to be substantially in engagement with the inner wall thereof at one point, there of course being a point of maximum clearance between the rotor and casing diametrically opposite the point of closest proximity of the rotor to the casing. The fluid is taken into the clearance space at the point of maximum clearance, and is then compressed in advance of the impellers and discharged from the clearance space as the impellers travel to the point of minimum clearance. The discharge from the fluid undergoing compression occurs by way of ports formed in the casing and communicating with the compression space between the rotor and casing. According to my preferred construction, the discharge port arrangement comprises a series of lateral ports opening from the periphery through the sides of the rotor and registering, throughout the period of compression, with ports in the casing end plates, through which the fluid is discharged into exhaust passages at opposite ends of the casing.

It may be mentioned that the present form of pump is similar in certain respects, particularly with regard to the construction of the rotor, to the type of engine described in my copending application on Rotary engine, filed January 10, 1930, Ser. No. 419,843.

Further objects and characteristics of the present invention, as well as the various details thereof, will be most readily understood from the following detailed description of a typical form of pump illustrating a preferred embodiment of the invention, reference be-

ing had for purposes of description to the annexed drawings, in which:

Fig. 1 is an end view of the pump with the end closure of the casing removed, a portion of the rotor and casing being shown in 55 medial section;

Fig. 2 is a section on broken line 2-2 of Fig. 1;

Fig. 3 is a perspective view of the rotor body;

Fig. 4 is an end elevation of Fig. 2 as viewed from the right thereof;

Fig. 5 is a section on line 5-5 of Fig. 2 showing particularly the exhaust port arrangement in the casing end plate;

Fig. 6 is a detailed sectional view of one of the rotor blades; and

Fig. 7 is a fragmentary end view similar to that portion of Fig. 1 shown in elevation, illustrating a variational form of port arrangement.

Referring first to Figs. 1 and 2 of the drawings, the rotor casing comprises a cylindrical shell 10 having an integral base portion 11, there being a pair of end closures or plates 12 and 13 secured to the shell by screws 14. The pump rotor, generally indicated at R, is carried on a shaft 15 mounted eccentrically, relative to the axial center of the shell, the shaft being journaled in bearings 16, 16a, inserted within annular recesses 17 formed in the casing end plates. The body of the rotor comprises a wheel 19, having a general cylindrical shape, mounted on an enlarged portion 15a of the shaft. The rotor wheel is secured to shaft flange 15b by means of screws 20, and to ring 22 keyed to the opposite shaft near the end of the enlarged portion 15a, by means of screws 21. The heads of the screws are counter-sunk in the outer faces of flanges 15b and ring 22, as indicated.

The rotor wheel preferably is shaped so as to form flanges 19a, the end faces of which have a fairly close fit with the casing end plates in order to minimize the tendency for leakage to occur around the rotor during compression of the fluid in the peripheral space between the rotor and the casing, as described at a later point. Leakage around the rotor will occur to the point of filling annular

spaces 23 between the rotor and the casing end plates, further leakage from spaces 23 around the rotor shaft and through the casing being prevented by suitable means, for example, packing glands 18. It may be mentioned that my invention is in no way limited to the particular form of rotor wheel shown, or the particular mounting of the rotor shaft within the casing, hence it will be understood that numerous other forms of rotor construction and mounting may be employed without departure from the essence of my invention.

A plurality of radial slots 24 are formed in the rotor at equal angular intervals, the slots extending radially inward through the rotor flanges. Within each of the slots 24 is carried a radially movable blade or impeller 25, the blades being substantially the same width as the rotor wheel at its outer periphery. The blades preferably have a snug sliding fit within the radial slots. Each of the blades 25 has an integral shank 25a inserted within a radial bore 26 drilled in the rotor wheel at the base of the slot, there being sufficient clearance at 27 between the shank and the bore wall to permit the insertion of a coil spring 28, which serves to thrust the blade radially outward against the inner peripheral wall of the casing.

A pair of parallel grooves 30 are formed longitudinally in the outer ends of blades 25, each of the end grooves continuing respectively in grooves 31 and 32 formed in the opposite sides of the blade. Within each end groove 30 and its corresponding side groove is an angle-shaped seal leaf 33, between the inner side of which and the base of the groove is placed marcel springs 34. By thus providing for each blade, two separate leaves extending on opposite sides thereof, and each capable of individual lateral movement relative to the blade, by the action of the marcel springs, an effective seal is provided between the edges of the blades and the casing wall.

The rotor wheel is eccentrically positioned within the casing, and has a predetermined amount of clearance at 36 from the casing wall. The degree of eccentricity of the rotor within the casing is such that the rotor substantially engages the inner wall of the casing at a point 35, which point is predetermined in accordance with the position of the inlet and the angular spacing between blades. Fluid is taken into space 36 between the rotor and casing from inlet 37, the mouth of the inlet within the casing being shown in the present instance to terminate at a point 37a in vertical alinement with the rotor shaft. In order that the maximum volume of fluid may be taken into the peripheral space between successive blades, the eccentric position of the rotor is determined so that the point 35 of closest proximity of the rotor to the casing wall will lie on a diameter bisect-

ing the angular distance between two successive blades, after the last, (in the direction of rotation of the rotor as indicated by arrow A, see Fig. 1) just moves past the inlet at point 37a. Thus in the illustrated form of pump wherein I show the rotor to carry eight blades, point 35 will be located at approximately $22\frac{1}{2}^{\circ}$ clockwise of the vertical center line L of the casing, on a diameter bisecting the angular distance between blades B and C in the positions shown, the midpoint of space 36a between blades B and C being the point of greatest clearance between the rotor and casing. It will be understood, of course, that the rotor may carry any desired number of blades and that the position of the rotor within the casing relative to the inlet may be varied accordingly. For example, assuming there to be four symmetrically arranged blades on the rotor, the point of engagement or of closest proximity of the rotor to the casing would be located at a point substantially 45° clockwise of the vertical center line L.

Although any suitable arrangement of exhaust ports may be provided in the casing whereby the fluid may be discharged from space 36 during compression, I prefer to arrange the ports in a manner such that the fluid may be discharged laterally through the side, and preferably both sides, of the rotor, instead of discharging the fluid directly from space 36 at a point beyond the periphery of the rotor. A plurality of recesses 40 are formed in the rotor wheel between successive blades, there also being formed ports 41 leading from the recesses through opposite sides of the rotor. During compression of the fluid within space 36 as it is carried in advance of the blades, fluid is discharged through lateral ports 41 into circularly extending exhaust conduits 43, which may conveniently be cast integrally with the casing end plates, by way of arcuate ports 45 in the end plates, these ports being coextensive with conduits 43 for a predetermined distance determined by the interval during which compression occurs. The center of curvature of conduits 43 and ports 45 is, of course, at the center of the rotor shaft.

In the operation of the pump, fluid is taken from inlet 37 into space 36 between successive blades, and is compressed from a maximum volume 36a and progressively discharged from the clearance space into exhaust conduits 43 by way of ports 45 during the travel of the blades from the point of intake to point 35, at which point ports 41 are closed to the exhaust passages by their movement beyond the end of the arcuate ports 45. Initial discharge occurs at that point at which ports 41 are brought into registration with the lower end of ports 45, this initial discharge occurring just after a full volume of fluid has been drawn in and

sealed between successive blades after the last has moved past point 37 or the edge of the inlet. The start of intake may occur at any suitable point after the blades have moved past point 35, initial uncovering of the inlet port being shown to occur at a point 48 substantially the distance between blades from point 37a.

As previously mentioned, the invention in its broader aspects contemplates the arrangement of the discharge ports at any suitable location in the casing shell or end plates. For purposes of illustrating one variational embodiment of the invention, I have shown in Fig. 7 a pump generally similar to the described form except that the rotor wheel 191 has between blades a smooth peripheral surface, and the discharge ports are located so as to enable the fluid to be expelled directly from the sides of the compression space instead of by way of passages in the rotor. According to the construction shown in Fig. 7, fluid in the compression space 36 is discharged through ports 60 formed in the casing end plates in a manner similar to ports 45 in the previously described form, except that ports 60 are located substantially adjacent the inner wall of the shell 10 so as to enable the fluid to be expelled from the compression space entirely at the outside of the rotor. The angular or circular extent of each set of ports 60 will, of course, be substantially the same as that of ports 45.

It will be understood the drawings and description are to be considered merely as illustrative of and not restrictive on the broader claims appended hereto, for various changes in design, structure and arrangement may be made without departing from the spirit and scope of said claims.

I claim:—

1. In a rotary pump, a casing comprising a cylindrical shell having end closures, a cylindrical rotor mounted eccentrically within the casing so as to substantially engage said shell at one point, there being a compression space between the rotor and said casing shell, a plurality of radially movable blades mounted on the rotor, a fluid inlet opening into said compression space, concave recesses formed in the cylindrical surface of said rotor between adjacent blades, said recesses being substantially coextensive in length with the angular distance between adjacent blades and opening through the periphery of the rotor throughout their respective lengths, a discharge port in one of said end closures between the point of maximum clearance between the rotor and casing and the point of engagement of the rotor with the casing, and a plurality of lateral ports extending from said concave recesses in the rotor through one end of the rotor and adapted to register with said discharge port.

2. In a rotary pump, a casing comprising a

cylindrical shell having end closures, a cylindrical rotor mounted eccentrically within the casing so as to substantially engage said shell at one point, there being a compression space between the rotor and said casing shell, a plurality of radially movable blades mounted on the rotor, a fluid inlet opening directly into said compression space through said cylindrical shell, concave recesses formed in the cylindrical surface of said rotor between adjacent blades, said recesses being substantially coextensive in length with the angular distance between adjacent blades and opening through the periphery of the rotor throughout their respective lengths, discharge ports in both of the casing end closures between the point of maximum clearance between the rotor and casing and the point of engagement of the rotor with the casing, and a plurality of lateral ports extending from said concave recesses in the rotor through both ends of the rotor and adapted to register with said discharge port.

3. In a rotary pump, a casing comprising a cylindrical shell having end closures, a cylindrical rotor mounted eccentrically within the casing so as to substantially engage said shell at one point, there being a compression space between the rotor and said casing shell, a plurality of radially movable blades mounted on the rotor, yielding means urging said blades radially outward, a fluid inlet opening directly into said compression space through said cylindrical shell, concave recesses formed in the cylindrical surface of said rotor between adjacent blades, said recesses being substantially coextensive in length with the angular distance between adjacent blades and opening through the periphery of the rotor throughout their respective lengths, discharge ports in both of the casing end closures between the point of maximum clearance between the rotor and casing and the point of engagement of the rotor with the casing, and a plurality of lateral ports extending from said concave recesses in the rotor through both ends of the rotor and adapted to register with said discharge port.

In witness that I claim the foregoing I have hereunto subscribed my name this 12th day of December 1929.

DIMITRI N. HAPKINS.
